UNITED STATES PATENT OFFICE.

MEIER G. HILPERT, OF BETHLEHEM, PENNSYLVANIA.

CHILD'S SLIDE.

Application filed July 6, 1923. Serial No. 649,966.

The present invention relates to exercising and amusement slides particularly adapted for children.

One of the principal objects of the invention is to provide a slide of the type mentioned which has no supports and is easily transportable by children from one position to another, being particularly designed to utilize as supports such articles as stairways, 10 chairs, beds, tables, and the like.

Another one of the principal objects of the invention is to provide a slide of the character mentioned which combines the properties of safety, durability, strength and lightness, 15 thus adapting it to be handled, set up and used by children of rather tender years.

The principal features of novelty are as follows:

1. The slide is light in weight so that children can easily handle and transport the same.

2. Although the slide is light in weight, it has a maximum strength for said weight, being strong enough so that heavy adults can 25 use the slide without injuring it.

3. The slide is of such length that it can be passed through the usual doorways and can be easily stored in closets and the like.

4. No securing means is required to set up 30 the slide ready for use. It is constructed so that it may be supported at the high end on the tread of a stairway, chairs, tables, beds, etc. The slide is constructed so that it will rest on flat supports such as a tread of a stairway, table-top, and the like without fear of displacement, or it can be supported by a rail such as at the top of a chair, fence or bed, the slide having a projection adapted to hook over such rail.

40 5. The slide is convexly curved at its upper end to afford a seat for the child when mounting the slide and starting to coast. This curved portion also adapts the slide for support at its upper end on flat surfaces, the curve affording a clearance between the slide and the front edge of the flat surface.

6. The side flanges of the slide, at the upper end, are cut away so as to afford easy access to the slide at said end.

50 7. The slide at its lower end is concavely curved so that it may rest on a flat surface such as a floor, and discharge the child substantially tangentially with the floor without any drop, thereby eliminating the chances of

possible injury due to the drop that the child 55 is subjected to with the usual type of slide.

8. The slide is provided at its lower end with a flexible flap which forms a floor or ground covering to receive the child leaving the slide, thus protecting the child from 60 splinters or slivers in the floor, and from dirt, sand, etc., and eliminating the chances of tearing or soiling the child's clothes. This flap may be marked at regular intervals with 65 transverse lines for the purpose of determining the distances that the child slides, thus giving the device a game value in addition to the pleasure obtained from the mere coasting down the slide.

9. At its upper and lower ends the slide 70 may be provided with transverse bearing members which project laterally from the sides of the slide, thus adding to the stability of the slide and keeping the same out of contact with baseboards, etc. Because of these 75 projecting transverse members it is impossible for a child to pinch its fingers between the slide and the base-board.

10. The lower or bearing surfaces of the transverse members may be curved convexly 80 so that the slide always has a normal bearing on its flat supports. Because of this feature there is no component of the weight of the slide or child to cause longitudinal movement of the slide.

11. The slide comprises side members or flanges which support the slide-way and the slide-way is secured to said members or flanges in such a manner as not to weaken said flanges or members.

Other objects and features of novelty will 90 be apparent from the description taken in connection with the drawings in which,

Figure 1 is a plan view of a slide constructed in accordance with the present invention.

Figure 2 is a side elevation of such a slide.

Figure 3 is an end elevation of the slide.

Figure 4 is a plan view on a larger scale of the lower end of the slide, showing a flexible flap secured thereto and adapted to form a 100 floor or ground covering to receive the children as they shoot out from the end of the slide.

Figure 5 is a side elevation of the structure shown in Figure 4.

Figures 6, 7, 8 and 9, are transverse sectional elevations of the slide illustrating several structural modifications.

Figures 10 to 17 inclusive illustrate the slide supported on various objects, Figures 10, 12 and 14 showing the slide supported on the tread of a stairway having different inclinations.

Figures 18 and 19 illustrate the manner of securing two or more slides together to form in effect a single long slide.

Figures 20 and 21 illustrate the slide supported at its upper end on a railing of a fence and on the seat of a chair, respectively.

Figures 22 and 23 are longitudinal and transverse sectional views respectively, of a modified form of slide.

15 The slide of the present invention, although adapted for outdoor use in connection with terraces, porches, fences, etc., is primarily designed for indoor use, that is to say, in houses or apartments. For this purpose, according 20 to the present invention, the slide is so constructed that it can be easily transported by children from one place to another, easily stored, and can be set up on various articles found in the average house or apartment, 25 and at elevations to provide good and safe inclinations according to the age of the child.

To these and other ends the slide consists simply of a slide-way without any attached supports. One or both of the end portions of 30 the slide-way may be curved to present a convex seat portion at its upper or receiving end, and if the lower end is curved, a concave delivery seat portion at its lower end.

The curvatures are such that at all angles at 35 which the slide may be set up, a substantially horizontal seat is provided at the receiving or upper end, and the child is delivered in a substantially horizontal direction (see Figs. 10 to 17, and 20 to 22). Moreover, the reverse curvatures mentioned above 40 add to the stiffness of the slide which, together with other features of construction hereinafter described, gives a slide combining great strength with minimum weight.

45 The slide illustrated in Figures 1 to 21 inclusive, includes a pair of side flanges or beams 10, a slide-way 11, and end bearing members 12. The slide is adapted to be supported solely at its two ends without any securing means, the beams 10 transmitting the 50 load from the slide-way to the supporting surfaces through the end bearing members 12. Preferably the under surfaces of the end bearing members are convexly curved so that 55 the slide is adapted, no matter at what angle it is positioned, to give equal, sufficient and true or normal bearing on flat supporting surfaces. This construction eliminates any such 60 tendency of the slide to slip on its supporting surfaces as occurs when a slide is set against the edge of a table or stairway. Where the 65 support surfaces are horizontal, as usually is the case, the weight of the slide and its load will be transmitted vertically to said surfaces, there being no horizontal components

of the weight tending to move the slide longitudinally. This is an important feature not only from the standpoint of safety, but also because it enables the slide to be supported on articles of furniture and household fixtures without danger of injury to the bearing surfaces.

70 Preferably the transverse bearing members 12 project a substantial distance from the side beams 10 on each side thereof. This construction makes the slide very stable, preventing it from turning over sideways even though the child should lean far over the side. Furthermore, these supports provide 80 a rigid base even when the slide is placed on a yielding support, such as a chair cushion or a bed mattress.

Another advantage of this construction resides in the fact that the projecting portions 85 of the transverse members act to space the slide-way from a wall or washboard, thereby making it impossible for the child's hand or fingers to be caught between the slide and the wall or wash-board. It also prevents the child from rubbing against such wall or board when sliding, thus eliminating the chance of damaging the wall or injuring the child. This construction also permits using 90 a narrow slide-way having even greater stability and strength than a wide slide-way, 95 for the reason that the load is necessarily more centered with respect to the base or supports of the slide.

100 The seat or slide-way 11 consists preferably of a number of thin strips of wood supported on cross members 13, which are attached to the side beams by corner members 14, 14', 14'' and 14''' (see Figs. 6, 7, 8 and 9). The strips forming the sliding member may have tongued and grooved joints as shown in Figs. 105 6 and 7, thus permitting the strips to be secured to the cross pieces 13 by nails or brads 11¹, the heads of which are covered, or they may be connected in any other suitable manner. As shown in Figure 8, the strips 11² may 110 be spaced from each other and attached to the cross members 13 by nails, screws, or the like, inserted from the bottom of the cross members 13. It is also within the scope of the invention to use a slide-way of sheet material. 115 Such a modification is shown in Figure 9, where the slide-way is shown at 11³.

120 The corner pieces 14, 14', 14'' and 14''' are disposed within the side beams and not below the same, and are secured to the side beams by screws 8', or the like, which pass through said beams well above the lower edges thereof. This construction provides a maximum under 125 clearance for the slide, enabling it to clear, for instance, the noses of intermediate stair treads without necessitating excessive top and bottom "reach" curves, whereby the slide may be used in connection with highly polished steps or the like without the least injury 130

thereto. This construction is also important because it in no way weakens the side members. If the cross members 13 were attached to the side members by screws or nails driven 5 into the lower edge of the side beams, the very fibres of the beams which are subjected to the greatest stress, would be cut, thereby greatly weakening said beams. For instance, if the side beams were one-half inch thick, and one-quarter inch screws were employed for securing 10 the cross members to the bottom edges of the side beams, fifty per cent of the strength of the side beams would be lost, for the reason that the screws would sever fifty per cent of 15 the fibres at the lower edges of the side beams.

With the construction as shown in the drawings, none of the fibres at the lower edges of the side beams is injured, and consequently the full strength of said beams is utilized. As 20 compared with the case mentioned above where the side beams were one-half inch thick and one-quarter inch screws were used, a slide constructed in accordance with the present invention with side beams one-half inch thick, 25 would be one hundred per cent stronger.

As shown in Figs. 6 and 7, the cross pieces 13 are attached to the side beams by metal angle pieces, 15, and the screws 8 pass through the side beams, the angle pieces, and into the 30 corner pieces 14. In Figs. 8 and 9, the cross pieces 13 are fastened directly to the corner pieces 14' and 14'', respectively. As shown in Fig. 2, the side flanges or beams are each composed of a straight strip having end extensions 16 and 17 fastened thereto, as by means of the angle irons 18 and 19. These 35 angle irons reinforce the beams at the two ends thereof and form tension flanges at the joints between the extensions 16 and 17 and 40 the main portions of the beams.

Preferably the slide, at its lower end, is provided with a flexible flap 20, of oil-cloth or the like, which is adapted to be folded over into the slide-way when the slide is stored or 45 shipped. This flap may be secured to the under side of the lower transverse member 12, as by means of brads 20'. The purpose of the flap is to form a floor or ground covering to receive the child shooting from the end of the 50 slide-way, thus providing a protection for the child against splinters or slivers in the floor and acting to prevent the child's clothes from being torn or soiled. If desired, the flap may be marked at regular intervals with transverse lines 20², for the purpose of marking the 55 distance that the child slides beyond the lower end of the slide-way. These lines may be numbered so that a value can be given to the distance that the child slides. In this manner 60 the slide is given an interesting game value in addition to its use merely as a slide.

As shown, the transverse bearing members 12 may be formed with holes 23, for spikes or the like, in case it is desired to support the 65 upper end of the slide on an inclined surface

such as a terrace. These holes are also employed when two or more slides are joined together to form a single long slide as shown in Figs. 18 and 19. For this purpose the delivery end bearing member 12 of one slide is 70 positioned on the receiving end flanges of another slide and the parts secured together by several wraps of a rope or endless straps 21, placed around the adjacent projecting ends of the bearing members 12. Transverse 75 movement of the lower end of the upper slide with relation to the adjacent end of the lower slide may be prevented by spikes 22 inserted through the holes 23, and movement of the upper ends of both slides may be prevented by 80 additional spikes 22 inserted through the holes and into the ground.

Referring to the various figures of the drawings, it will be noted that the side beams or flanges at the upper or receiving end of the slide are gradually reduced in height as they approach the said end. This is for the purpose of permitting the child to easily mount the slide from the side, it being merely necessary for the child to assume a sideways seating position at the upper end of the slide and then swing its legs over the flange and into the slide-way. 90

Figs. 10 to 22 inclusive, show the slide supported in various ways. An examination of these views will show better than words can express, the utility and great adaptability of the slide for both indoor and outdoor use. Figs. 10, 12 and 14, show how the slide may be used on stairways of different inclinations, and Fig. 16 how the slide may be supported on different treads of the same stairway to obtain an inclination of the slide adapted for the particular child using the same. 100

For very young children the slide would 105 be placed on the lowest tread, as shown in full lines on said figure. It is one of the main features of this slide that it is adapted to be supported for use so that it will be inclined through a wide angular range whereby it 110 can be positioned to be safely used by very young children, or positioned at a steeper angle for older children.

Figs. 22 and 23 illustrate a modified form 115 of the invention. In this form, the slide comprises metal side pieces 24 which may be of the flat form shown, or of gas pipe, and slide-way or seat member 25 of sheet material, cross pieces 26 and hand or guard boards 27. The seat member of slideway 25 is curved 120 transversely as shown in Fig. 23, has a flat receiving portion 25' at the upper end of the slide-way, and a concave delivery portion 27 at the lower end of the slide. The upper end of the slide is provided with a transverse bearing member 28. As shown, this is integral with the slide-way and made by bending over a portion of the upper end forming the flange or bearing portion 28. At the 125 lower end of the slide the side pieces 24 are 130

curved concavely to provide the bearing member 29, adapting the slide to rest securely on flat supporting surfaces. The side members 24 may be secured to the slide-way and hand 5 or guard boards 27 by screws or bolts 30, or the slideway 25 and side members 24 may be spot-welded together.

Although two forms of the invention have been described in detail, it is to be understood that the invention is not thus limited but includes modifications and changes which come within the scope of the appended 10 claims.

Having thus described the invention what 15 is claimed as new and desired to be secured by Letters Patent is:

1. A child's exercising and amusement slide readily portable by a child and adapted to be supported on various articles, having 20 transverse end bearing members projecting from the under side thereof, said members having convex bearing surfaces on the bottoms thereof, whereby the slide will bear normally at its two ends on surfaces of different 25 levels.

2. A child's exercising and amusement slide readily portable by a child and adapted to be supported on various articles, having transverse end bearing members secured to 30 the under side thereof and projecting laterally therefrom at each end.

3. A child's exercising and amusement slide readily portable by a child and adapted to be supported on various articles, having 35 a convexly curved seat portion at its upper end and having a transverse end bearing member projecting from the lower side of said seat member provided with a convex surface on the bottom thereof and adapted 40 to support the slide on a level surface or to hook over a narrow support.

4. A child's exercising and amusement slide readily portable by a child and adapted to be supported on various articles, consisting 45 of a channel having an angularly extending upper portion presenting a substantially horizontal seat and a concavely curved delivery portion and having end bearing members provided with convexly curved bearing 50 surfaces on their lower sides adapted to support the slide normally at different angles of inclination.

5. A child's exercising and amusement slide readily portable by a child and adapted 55 to be supported on various articles, comprising a channel having oppositely inclined end portions and having end bearing surfaces projecting from the under side thereof, said surfaces being shaped to transmit the weight 60 of the slide and its load normally to the supporting surfaces.

6. A child's exercising and amusement slide readily portable by a child and adapted to be supported on various articles, comprising 65 a channel having reversely curved end

portions and transversely extending end bearing members secured to the under side of the channel and having rounded surfaces, whereby the weight of the slide and its load is transmitted normally to the supporting 70 surfaces.

7. A child's exercising and amusement slide readily portable by a child and adapted to be supported on various articles, comprising a channel having a convexly curved receiving end and having a relatively wide transverse end bearing member secured to the under side of said receiving end, said bearing member having a bearing surface disposed a sufficient distance from said channel to enable the slide to clear the edge of a flat supporting surface and to rest on said flat surface through said bearing member without marring said surface. 75

8. A child's exercising and amusement slide readily portable by a child and adapted to be supported on various articles, comprising a channel having reversely curved end portions provided with convexly curved supporting surfaces on the under side thereof, the flanges of the channel at the upper end portion thereof gradually decreasing in depth toward the end to permit easy mounting of the slide from the side. 90

9. A child's exercising and amusement slide readily portable by a child and adapted to be supported on various articles, comprising a channel having reduced flanges at each end and rounded supporting members for normal bearing on flat surfaces at different 95 levels. 100

10. A child's exercising and amusement slide readily portable by a child and adapted to be supported on various articles, comprising side beams, a seat member secured thereto, bearing members secured to the under side of said seat member at the ends thereof, said bearing members having rounded surfaces, whereby the slide will bear normally at its 105 two ends on surfaces of different elevations. 110

11. A child's exercising and amusement slide comprising a channel having a convexly curved receiving end and a concave delivery end, combined with a flexible sheet secured to the under side of the delivery end adapted to form a floor or ground covering to receive the child at the foot of the slide, said sheet having a plurality of longitudinally spaced indications on its upper face. 115

12. A child's exercising and amusement slide adapted to be supported solely at its two ends, comprising side beams, a seat member, and means for securing the seat member to the side beams comprising corner strips engaging said beams and seat member, fastening devices passing through said beams well within the marginal portions thereof and into said corner pieces and other fastening devices securing said corner strips to said seat member. 120

125

130

13. An amusement and exercising slide of such weight that a child can transport the same and of such length that it can be easily passed through a doorway of usual size, comprising a relatively long slide-way, the end portions of which are inclined with respect to the central portion, and projecting in opposite directions from said central portion; the upper of said end portions adjacent its tip end having a narrow transversely extending part projecting slightly from the bottom face of the slide, the under surface of said part constituting a narrow bearing surface for the corresponding end of the slide, where-
10 by the upper end of the slide may be sup-

ported on any horizontal surface such as a tread of a stairway or table without liability of displacement or supported on a rail such as the top of a chair or fence by hooking the said transverse part over said rail. 20

14. A child's exercising and amusement slide, comprising a channel, and a member connected to the lower end of said channel adapted to form a floor or ground covering to receive the child at the foot of the slide, said member being foldable into said channel when the slide is not in use. 25

In testimony whereof I hereunto affix my signature.

MEIER G. HILPERT.
